PACKING-HEAD FOR DEEP WELLS.

1,071,360.

Specification of Letters Patent. Patented Aug. 26, 1913.

Application filed December 14, 1912. Serial No. 736,666.

To all whom it may concern:

Be it known that we, the undersigned, JAMES E. SHIERY and JOHN SHIERY, citizens of the United States, residing at Geneva, 5 Adams county, Indiana, and Bridgeport, in the county of Lawrence and State of Illinois, respectively, have invented certain new and useful Improvements in Packing-Heads for Deep Wells, of which the following is a specification.

This invention relates to improvements in equipment for deep wells, such as oil and gas wells.

The object of the invention is to provide 15 a packing device or appliance capable of being used at the top section of the well tubing, and of being supported at operative position by the well casing. These general objects and other purposes of the invention 20 which will be apparent as the nature of our invention is better understood, are accomplished by the mechanism illustrated in the accompanying drawings wherein the several parts of the device are identified by 25 suitable characters of reference.

Figure 1, is a top plan view, and Fig. 2 is a vertical central longitudinal sectional view of our invention.

The cylinder A has the integrally formed 30 annular flange A¹, and is provided with the machined bore A². The lower end of the cylinder is threaded to receive the coupling 1 of the usual well tubing 2. From a location near the bottom of the cylinder there 35 extends a port or passageway B whose upper end terminates at a location above the flange A¹ and opens into a discharge pipe C that is screwed in a boss A³.

A support ring D has a seat D¹ upon 40 which the flange A¹ of the cylinder loosely fits. To connect together the cylinder and the support ring, the latter is so placed that its ears D² will pass the recesses A³ in the flange, when, at shifted position, one on the 45 other, these members are held in loose engagement with each other. The ring D is internally threaded to be screwed down on the usual well casing 3.

The member E, is designated as the piston 50 sleeve. This sleeve has a bore of suitable diameter to permit the passing therethrough of the well piston rod or "wire" 4. Secured to the top of the sleeve E is a clamp F. This clamp is so made that by tightening 55 the bolts F¹ the clamp will grip tightly

the piston rod so that the sleeve will travel therewith. At the lower end of the sleeve, cups E¹ and E², secured by suitable means as shown, constitute a closure of the bore A².

Our improved packing appliance consists 60 of the cylinder, the support ring, and the sleeve, as shown. The support ring and cylinder are provided with the ears D² and recesses A³ respectively, to afford such connection between the two that handling and 65 transporting this appliance as an article of manufacture may be facilitated, and to also hold the cylinder against tendency to rise, even slightly, with the upward movement 70 of the piston.

To install the invention the support ring is detached from the cylinder and screwed down on the well casing. The cylinder with its well tubing is then let down to place, the flange A¹ coming to rest on the seat D¹. 75 The next step is to let down over the piston rod 4, the sleeve E. The arrangement whereby the leather cups E¹ and E² which constitute the closure of the bore A², are retained is as follows: The collar E³ holds 80 the cup E¹ against the ring E⁴. The function of the ring E⁵ whose bore fits the piston rod is to hold the cup E² securely 85 against the collar E³. When the piston is adjusted to proper height with reference to the cylinder, and the bolts F¹ are tightened, the installation of the invention is 90 complete.

A well packing appliance constructed in accordance with our invention is adapted to 95 be easily applied to use at any well of the character herein referred to. It is economical of manufacture, easy to install, and is not liable to be broken or deranged. Another advantage is that packing of the well 100 head is entirely practicable where the small sized or "wire" piston rods are used.

In operating the well provided with this invention escape of the liquid at the piston rod is prevented by the packing cups E¹ and E², and at the same time a steadyng of the piston rod against lateral vibration is had. The liquid raised in the tubing passes freely 105 through the ports B and the discharge pipes C.

What we claim as our invention is:

1. An appliance for deep wells, comprising a cylinder capable of being supported by the well casing and of having connection at its bottom with the well tubing, there 110

being ports extending from the lower portion of the cylinder bore to the top of the cylinder, a sleeve adapted to be connected to the well piston and to move reciprocatingly in the bore of the said cylinder, and packing between the said sleeve and the cylinder bore.

2. An appliance for deep wells, comprising a support-ring to be secured to the well casing, a cylinder detachably connected to and supported by the said support ring there being ports extending from the lower portion of the cylinder bore to the top of

the cylinder, a sleeve adapted to be connected to the well piston, and packing between the said sleeve and the cylinder bore. 15

In testimony whereof we affix our signatures in presence of two witnesses.

JAMES E. SHIERY.
JOHN SHIERY.
